HENRY M. LEONARD, OF RIDGEWOOD, NEW YORK

FLYING MACHINE

Application filed March 14, 1931. Serial No. 522,555.

This invention relates to new and useful improvements in flying machines and has more particular reference to those of the amphibian type.

For the purpose of this specification the term "G. A. L." will stand for the combined term gillaileron lead wherein "G" stands for gill, "A" stands for aileron, and "L" for lead or leading edge. The term "G. A. L." will be used to mean a superleading edge on the wing or wings of the machine.

It is one object of this invention to construct a G. A. L. having three different operating positions; namely, one, a closed position or fall position; two, a neutral or central position; and three, an extremely high or raised position.

For the purpose of this specification the latter two positions of the G. A. L. mentioned above will be known as being in floating positions, that is, they are operated by a stream of air directly attacking them on their own respective leading edges and thereby exposing the wing or airfoil leading edge, which combined, forms the superleading edge of the craft.

As another object of this invention it is proposed to construct the gillaileron (lead) to operate similar to the gills of a fish or resemble them. They should be closely fitted on the wings' leading edge and have the same curvature of their respective cambers, upper and lower, and having a horizontal position (that is opposite to a fish) in that they are in vertical position on a fish while on the instant device they are horizontal.

It is a still further object of this invention to construct the G. A. L. so that when in closed positions they are hardly noticeable because they are not separated from the wing but are merely lying tangent on the leading edge, when in operation while still in a lower position, they represent a somewhat broken looking leading edge and moving in a semi-

circular position by the force of push or connecting rods attached to them.

A still further object of this invention is to construct the G. A. L. to rise and fall so that when they are in an extended or raised position they are known to be floating in midair and may function just the same in their floating position (as well as in their neutral or central position); and also in their extreme lower or fall position.

Furthermore this invention proposes the construction of the G. A. L. with suitable pivots on their extreme nose on which they should be hinged for moving forward and backward by means of a push or connecting rod and to arrange them double on each wing, one being on the upper and the other on the lower camber on the right and left sides.

Furthermore as another object of this invention it is proposed to construct the G. A. L. with long streamlined levers on which they hinge and every lever being connected and housed between two nose ribs entirely enclosed and attached direct to the drag-struts of the wingspans.

One of the main reasons for constructing the G. A. L. is to maintain an unbroken or reduced lifting airfoil surface or wing and a full airfoil having controllable wing banking, turning, safety, slow-landing, and stabilizing means to maneuver the craft.

It is a still further object of this invention to provide suitable covered spaces accessible for repairing and inspecting the mechanical devices, such as inspection doors, vents and slides, for the maintenance and upkeep of the craft, and mechanical devices.

It is a still further object to arrange the inspection doors for the inspection of the various mechanically control means or devices of the craftwing; to arrange slides of thin metal strips so constructed and placed to move over the open spaces to cover or conceal them to prevent any foreign matter to

enter in the spaces as well as to reduce air resistance of the lever when raised, and also to provide small sliding shutters where the shafts of the G. A. L. travels and conceals them from any foreign bodies.

It is also proposed to provide vents in the trailing edge for the escape of air entering the enclosed spaced, internal compartments, when the G. A. L. are opened.

10 It is still further proposed to construct all the hinge levers and push rods in streamline shape and make them of non-corrosive material. Further, to enclose them in between two solid ribs of non-corrosive material to 15 prevent any foreign matter from entering the wing compartments.

One of the main reasons for constructing the G. A. L. on the leading edge is that they are to act as direct guides, leaders, and controllers, of the craft, and naturally since they guide, lead, and control the craft, the rest of the craft must follow in the same path or directions during normal flight or otherwise.

Another reason for constructing the G. A. L. on the leading edge is that on huge air-crafts the after ailerons are practically useless and a failure in case the craft is forced into a tailspin or nose dive and disastrous results follow; the G. A. L. will guide and 30 lead the craft and control same occurrence into a normal flying position, prevent tailspin, nose dive, and any other unnatural disturbance and provide a greater gliding angle, safe, slow landing speed, since should one of 35 the G. A. L. upper or lower get out of control or damaged by accident or otherwise, their opposite mating pair may be used to control the ship, and thereby provide a safer craft with means toward the safety of mankind 40 and promotion of aviation universally.

Should this plane be forced into a tailspin or nose dive, through some unknown reason, it may be averted by the G. A. L. use to guide the plane, by opening the gills, then reversing 45 the plane's motion into a counter clockwise turn, by the use of their mating pair of G. A. L., which have been especially constructed for a more rapid change to bank the ship, due to their shorter traveling distance 50 along their respective radii.

It is a further object to construct the G. A. L. to operate on a more rapid motion, since their respective traveling distance along their respective radii have been reduced to half the 55 distance, because the upper G. A. L. travels from its closed position or normal point on the upper camber to its motive position above the upper camber at about 30° approximately. Also do the lower G. A. L. function the 60 same, except that they travel in an opposite direction, from the lower camber's normal point, to its operating motive position along its respective circumferential radius.

For further comprehension of the invention, and of the objects and advantages there-

of, reference will be had to the following description and accompanying drawings, and to the appended claims in which the various novel features of the invention are more particularly set forth.

70 In the accompanying drawings forming a material part of this disclosure:—

Fig. 1 is a side elevational view of a craft constructed according to this invention.

Fig. 2 is an enlarged plan view of Fig. 1.

Fig. 3 is a front elevational view of Fig. 2.

Fig. 4 is a fragmentary enlarged edge elevational view looking in the direction of the line 4—4 of Fig. 2.

Fig. 5 is a view similar to Fig. 4, but with 80 an indicated position of the G. A. L.

Fig. 6 is another view similar to Fig. 4, but showing another adjusted position of the G. A. L.

Fig. 7 is a fragmentary enlarged sectional 85 view taken on the line 7—7 of Fig. 4.

Fig. 8 is a sectional view taken on the line 8—8 of Fig. 7.

Fig. 9 is a sectional view taken on the line 9—9 of Fig. 8.

Fig. 10 is a fragmentary enlarged detailed 90 view of the mechanism for controlling the G. A. L.

Fig. 11 is a sectional view taken on the line 11—11 of Fig. 10.

Fig. 12 is a sectional view taken on the line 12—12 of Fig. 10.

Fig. 13 is a fragmentary sectional view taken on the line 13—13 of Fig. 10.

Fig. 14 is a sectional view taken on the line 100 14—14 of Fig. 13.

Fig. 15 is a sectional view taken on the line 15—15 of Fig. 1.

The invention has been shown applied to 105 an amphibian type of flying machine. The complete details of this machine are not illustrated, since they form part of this invention but not described. It is thought sufficient that the main portions of this craft be re-

viewed so that the relation of the invention 110 as applied to it can be understood. For this purpose the reference numeral 10 indicates the whole of the craft, 11 the wind shield,

12 the landing gear, 13 the tail skid, 14 the 115 rudder, 15 the elevators, 16 the stabilizers, 17 the motor driven propeller, and 18 the main wings. The G. A. L., indicated by reference

120 numeral 19, are arranged upon the leading edge of the main wings 18 extending from the ends inwards substantially through a dis-

125 tance of one-third the length of the wings. In Fig. 1 dot and dash lines 20 indicate a pivoted position of the G. A. L. In Fig. 3 the dot and dash lines 21 indicate the extended position of the G. A. L.

The G. A. L. 19 is mounted upon each of the wings 18 and comprises an upper gill member 22 and a lower gill member 23 on

130 the leading edge of the wings and of shapes to form a leading edge and having the same

curvature. In Fig. 4 an edge elevational view of the G. A. L. is clearly seen and it should be noticed that they fit in with the formation of the wings themselves. When closed as shown in Fig. 4, the operation of the G. A. L. is as thought plain. It is only when the G. A. L. is opened, as for example as shown in Fig. 5 or Fig. 6, that there is any effect.

10 In the closed position of the G. A. L. as shown in Fig. 4, the front edges are immediately adjacent each other so that they touch, while the inside edges touch and are tangent to the contour of the wing. The outer surfaces are of such curvatures as to naturally fit in with the curvature of the wing. These gill members are provided with means for moving them directly away from each other to various positions off the wing and means 15 for tilting about their front axes in any of their various positions.

The means for moving the gill members directly away from each other to various positions off the wing comprises a vertical spar 25 shaft 24 having threads of different hands and supporting brackets 25 normally close to each other and arranged so that upon rotation of the spar shaft the brackets move simultaneously away from each other. The 30 spar shaft 24 is rotatively supported in standards 26 at its ends, which standards are mounted within the wing spars. Stud shafts 27 project from each of the brackets and are rotative in the brackets.

35 Hinge levers 28 rotatively connect on the stud shafts and extend frontwards and pivotally connect at 29 upon the front nose of the gill members. Gill rods 30 pivotally connect on the gill members intermediately of the 40 front and rear edges and are adjustably mounted upon the brackets 25. This adjustable mounting is obtained by reason of casting members 31 rotative on the stud shafts 27 and formed with a slot through which the 45 gill rods slidably pass. Gears 32 are fixed upon the stud shafts 27 and mesh with rack teeth 33 formed on the gill rods so that upon rotation of the stud shafts the rods are rotated.

50 A means is also provided for turning the spar shaft 24. This means is in the form of a worm wheel 34 fixed upon the spar shaft at its center so as to be located between the brackets 25 and meshing with a worm pinion 35 fixed upon a shaft 36 rotatively supported and carrying a bevel gear 37 in mesh with another bevel gear 38 upon a shaft 39 rotatively supported. A bevel gear 40 is fixed upon the shaft 39 and in mesh with a bevel 55 gear 41 on a rotatively supported shaft 42 which carries a bevel gear 43 meshing with a bevel pinion 44 upon a shaft 45 carrying a hand wheel 46 for its manual turning. Standards 47 serve to support the shaft 42.

The means for tilting the gill members

about their fronts as axes in any position, comprises a means for adjusting the gill rods 30. The latter means consists of a sprocket wheel 48 fixed upon the stud shaft 27 and engaged by a chain 49 engaged over a second sprocket 50 fixed upon a second stud shaft 51 rotatively mounted in the bracket 25. A pair of radial arms 52 project from each of the shafts 51. Cables 53 and 54 are respectively connected with the pair of arms 52 and extend over a drum 55 fixed upon a tubular member 56. Another pair of cables 57 and 58 connect with the radial arms 52 of the bracket and extend over a drum 59 fixed upon the same tubular member 56. The tubular member 56 has a flange portion 60 at its bottom end upon which push rods 61 pivotally connect at diametrically opposite sides. At the other ends the push rods connect upon a bracket 62 rotative upon the shaft 45. A hand wheel 63 is fixed upon the tubular member 62 for its manual adjustment.

To control the rudder of the craft, a pair of radial arms 64 are used which project from the bracket 62. Cables 65 from these radial arms extend to the rudder on opposite sides thereof for moving it one way or the other. The tubular member 62 is fixed upon a transverse tubular member 66 having tubular reduced portions 67. The shaft 42 extends through the tube 67 and 66. Radial arms 68 are fixed upon the tubes 67 and are for the purpose of controlling the elevators of the craft. For this reason cables 69 connect with the radial arms 68 and extend rearwards to the elevators. The dotted lines in Fig. 12 represent the position of radial arms 64 when the G. A. L. is separated.

In Fig. 14 it should be noticed that the drum 55 is keyed with keys 70 upon the tubular member 56 and the manner in which the cables 53, 54, 57 and 58 extend in opposite directions. In Fig. 13 a packing box 71 is shown closing the top end of the tubular member 56. A bearing 72 is positioned within a head member 73 on the packing box so as to allow turning of the shaft 39.

The landing gear 12 comprises a pair of wheels 75 which are retractable. Each of the wheels is mounted upon a stem 76 resiliently cushioned by shock absorbing rubber discs, structure 77 within a member 78. A screw thread arrangement 79 is formed within the casing member and connected with an extending shaft carrying a bevel gear 80, so that upon rotation of the bevel gear the wheel 75 is drawn upwards or extended outwards. A bevel gear 81 meshes with the bevel gear 80 and is fixed upon a shaft 82 extending completely across to the other side of the craft and is similarly connected for operating the other wheel. Bevel gears 80 and 81 are rotatively held in a suitable T shape mounting 82' designed so as to prevent jamming of the said gears when the landing gears

strike the ground heavily. A sprocket 83 upon the shaft 82 carries a chain 84 meshing with a sprocket 85 upon a control shaft 86. A crank 87 upon the shaft 86 is for the purpose of causing the retraction or extension of the wheels 75. Reinforcement struts 88 are connected upon one side of the frame 89 which surrounds the wheel and pivotally at 90 upon the hollow of the craft. The last described members are part of the present invention and will be claimed more specifically in a separate application.

A pair of controls is illustrated in Fig. 10 for selectively operating the G. A. L. on each end of the main wing 18. In Fig. 15 just one half of the ship has been shown with one of the controls. A second control is necessary. In operation, the craft may fly with the G. A. L. closed. Whenever it becomes necessary during different conditions of flying, the hand wheel 63 of one or the other of the controls may be turned for causing the upper and lower gill members of the G. A. L. to function around the pivot points 29.

The motion of pivoting may be traced from the hand wheel 63 down to the bracket 62, then by reason of the push rod 61 to cause pivoting of the tubular member 56. Thus the drums 55 and 59 are turned so as to pivot the shafts 51 in one direction or in the other depending upon the direction or turning of the hand wheel 63. The turning of the shaft 51 is transmitted to the stud shaft 27 so as to cause the gears 32 to turn and extend the gill rods 30 to cause the gill members 19 and 23 to simultaneously pivot about the points 29. In Fig. 5 the dot and dash positions indicate the pivoted positions of the gill members.

The gill members may be simultaneously separated from each other, for example to positions as indicated by full lines in Fig. 6, by turning the hand control 46. Motion from hand wheel 46 is transmitted to the worm pinion 35 and worm wheel 34. This causes turning of the shaft 24 and causes the parts 25 to move simultaneously towards each other or away from each other. Dot and dash lines 93 in Fig. 7 indicate another position of the brackets 25. In Fig. 7 reference numeral 94 indicates spar members within the wing of the machine. In Fig. 9 dot and dash lines 95 indicate pivoted positions of the supporting members 31 which guide the extension and retraction of the gill rods 30.

Struts 96 extend from the hollow of the ship up and supporting the wings 18. It is within these struts that all control cables and shafting extends so as not to expose these parts. The craft may be perfectly controlled with the G. A. L. mechanism and may be steered by operating the gill ailerons at one 45 of the ends of the wing 18.

While I have shown and described the preferred embodiment of my invention, it is to be understood that I do not limit myself to the precise construction herein disclosed and the right is reserved to all changes and modifications coming within the scope of the invention as defined in the appended claims. 70

Having thus described my invention, what I claim as new, and desire to secure by United States Letters Patent is:

1. In combination with a flying machine having wings, gill ailerons mounted on each wing and comprising an upper and a lower gill member on the leading edge of the wing and of shapes to form a leading edge and be tangent against said wing, a vertical spar shaft having threads of different hands, brackets engaging said threads, stud shafts projecting from said brackets, hinge levers rotative on said stud shafts and pivotally connected with the leading edges of said gill members, push rods pivotally connected on said gill members intermediately and adjustably on said brackets, and means for turning said spar shaft, means for moving said gill members directly away from each other to various positions off said wing, means for adjusting said push rods, and means for tilting said gill members about their front axes in any position. 85 90 95

2. In combination with a flying machine having wings, gill ailerons mounted on each wing and comprising an upper and a lower gill member on the lead edge of the wing, a vertical spar shaft having threads of different hands, brackets engaging said threads, stud shafts projecting from said brackets, hinge levers rotative on said stud shafts and pivotally connected with the leading edges of said gill members, push rods pivotally connected on said gill members intermediately and adjustably on said brackets, and means for turning said spar shaft, means for moving said gill members directly away from each other to various positions off said wing, means for adjusting said push rods, and means for tilting said gill members about their front axes in any position. 100 105 110

3. In combination with a flying machine having wings, gill ailerons mounted on each wing and comprising an upper and a lower gill member on the leading edge of the wing and of shapes to form a leading edge and to be tangent to said wing, a vertical spar shaft having threads of different hands, brackets engaging said threads, stud shafts projecting from said brackets, hinge levers on said stud shafts and pivotally connected with the lead edges of said gill members, gill rods pivotally connected on said gill member intermediately and adjustably on said brackets, and means for turning said spar shaft, means for moving said gill members directly away from each other to various positions off said wing, means for adjusting said gill rods, and means 115 120 125 130

- for tilting said gill members about their fronts as axes in any position, said means for moving said gill members directly away from each other to various positions off said wing, comprises a vertical spar shaft having threads of different hands, brackets engaging said threads, stud shafts projecting from said brackets, hinge levers on said stud shafts and pivotally connected with the lead edges of said gill members, gill rods pivotally connected on said gill members intermediately and adjustably on said brackets, and means for turning said spar shaft.
4. In combination with a flying machine having wings, gill ailerons mounted on each wing and comprising an upper and a lower gill member on the leading edge of the wing and of shapes to form a leading edge and be tangent against said wing, a vertical spar shaft having threads of different hands, brackets engaging said threads, stud shafts projecting from said brackets, hinge levers rotative on said stud shafts and pivotally connected with the leading edges of said gill members, push rods pivotally connected with said gill members intermediately and adjustably on said brackets, and means for turning said spar shaft, means for moving said gill members directly away from each other to various positions of said wing, means for tilting said gill members about their front axis in any position, said spar shaft being rotatively mounted at its top and bottom ends.
5. In combination with a flying machine having wings, gill ailerons mounted on each wing and comprising an upper and a lower gill member on the leading edge of the wing and of shapes to form a leading edge and be tangent against said wing, a vertical spar shaft having threads of different hands, brackets engaging said threads, stud shafts projecting from said brackets, hinge levers rotative on said stud shafts and pivotally connected with the leading edges of said gill members, push rods pivotally connected with said gill members intermediately and adjustably on said brackets, and means for turning said spar shaft, means for moving said gill members directly away from each other to various positions of said wing, means for tilting said gill members about their front axis in any position, the threads on said spar shaft being right and left respectively.
6. In combination with a flying machine having wings, gill ailerons mounted on each wing and comprising an upper and a lower gill member on the leading edge of the wing and of shapes to form a leading edge and be tangent against said wing, a vertical spar shaft having threads of different hands, brackets engaging said threads, stud shafts projecting from said brackets, hinge levers rotative on said stud shafts and pivotally connected with the leading edges of said gill members, push rods pivotally connected with said gill members intermediately and adjustably on said brackets, and means for turning said spar shaft, means for moving said gill members directly away from each other to various positions of said wing, comprising a worm on said spar shaft meshing with a worm pinion connected with a transmission terminating in a control handle.
7. In combination with a flying machine having wings, gill ailerons mounted on each wing and comprising an upper and a lower gill member on the leading edge of the wing and of shapes to form a leading edge and be tangent against said wing, a vertical spar shaft having threads of different hands, brackets engaging said threads, stud shafts projecting from said brackets, hinge levers rotative on said stud shafts and pivotally connected with the leading edges of said gill members, push rods pivotally connected with said gill members intermediately and adjustably on said brackets, and means for turning said spar shaft, means for moving said gill members directly away from each other to various positions of said wing, means for tilting said gill members about their front axis in any position, the adjustable connection of the gill rods upon said brackets comprising rack teeth on the gill rods meshing with gears fixed on said stud shafts, and said gill rods being slidable in members rotative on the shafts to maintain the contact of the teeth with the gears.
8. In combination with a flying machine having wings, gill ailerons mounted on each wing and comprising an upper and a lower gill member on the leading edge of the wing and of shapes to form a leading edge and be tangent against said wing, a vertical spar shaft having threads of different hands, brackets engaging said threads, stud shafts projecting from said brackets, hinge levers rotative on said stud shafts and pivotally connected with the leading edges of said gill members, push rods pivotally connected with said gill members intermediately and adjustably on said brackets, and means for turning said spar shaft, means for moving said gill members directly away from each other to various positions of said wing, means for tilting said gill members about their front axis in any position, comprising a worm on said spar shaft meshing with a worm pinion connected with a transmission terminating in a control handle.
9. In combination with a flying machine having wings, gill ailerons mounted on each wing and comprising an upper and a lower gill member on the leading edge of the wing and of shapes to form a leading edge and be tangent against said wing, a vertical spar

sition, said latter two means being associated with each other so as to terminate in a control wheel immediately adjacent to a second control wheel coaxially arranged for selectively controlling both of said means, a tubular member being connected with one of said hand wheels, and supporting a shaft therein connected with the second hand wheel.

10 In testimony whereof I have affixed my signature.
